W. H. PETIT

CONDENSER

Filed May 26, 1922

Inventor
WILLIAM H. PETIT.

Attorney
Edward Reed

UNITED STATES PATENT OFFICE.

WILLIAM H. PETIT, OF DAYTON, OHIO, ASSIGNOR TO THE MIAMI RADIO CORPORATION COMPANY, OF DAYTON, OHIO, A CORPORATION OF OHIO.

CONDENSER.

Application filed May 26, 1922. Serial No. 563,976.

This invention relates to condensers and more particularly to a variable condenser which is designed primarily for use with radio telephonic apparatus.

5 One object of the invention is to provide a simple, efficient condenser which will be very compact in form and which will have a relatively high capacity.

10 A further object of the invention is to provide a condenser of such a character that a plurality of condensers, or units, each complete in itself, may be connected together and operated under a single control to provide a condenser of a larger capacity.

15 A further object of the invention is to provide in connection with such a condenser a fine adjustment condenser which can be connected with and made structurally a part of the condenser, but will be operated 20 separately therefrom.

Other objects of the invention will appear as the device is described in detail.

In the accompanying drawings Fig. 1 is a sectional view taken centrally through a 25 condenser embodying my invention; Fig. 2 is an elevation of the inner side of one section of the casing; Fig. 3 is a detail view of the movable condenser plate; Fig. 4 is a detail view of one of the stationary condenser plates; Fig. 5 is a detail view of the dielectric; Fig. 6 is a sectional detail view 30 showing the manner of connecting together the two condensers; Fig. 7 is a detail view of the resilient washer; and Fig. 8 is a detail view of the connector bar.

35 In these drawings I have illustrated one embodiment of my invention, but it will be understood that this has been shown for the purpose of illustration only and that 40 various modifications may be made therein without departing from the spirit of the invention.

45 As shown in these drawings the condenser comprises a casing consisting of two sections 1 rigidly connected one to the other and arranged to provide between them a chamber within which the condenser plates are 50 located. As here shown, the two sections of the casing are identical and are interchangeable. Preferably each section of the casing consists of a disk of suitable insulating material having a circumferential flange 2 extending laterally from one face thereof, the flanges being so arranged that when the 55 flanged sides of two sections are placed to-

gether portions of the adjacent faces of the sections will be separated to provide the chamber. The two sections may be connected one to the other in any suitable manner, as by means of screws 3. Arranged within the chamber thus formed between the two sections of the casing are stationary condenser plates 4 which, in the present construction, are substantially semi-circular in shape and are supported on the respective 60 sections 1 of the casing. I prefer to mold the condenser plates 4 into the casing sections, the casing being preferably formed of bakelite or other similar material, which is readily molded. If desired, projections 5 65 may be struck from the condenser plates and embedded in the material of the casing to more firmly hold the plates in position thereon. The plates are seated for substantially their full thickness in the walls of the 70 casing so that their inner faces are substantially flush with the inner faces of the adjacent portions of the casing sections. Suitable means are provided for connecting the condenser plates in the circuit, and as here 75 shown each plate has rigidly connected therewith and preferably formed integral therewith a tongue, or projection, 6 which extends beyond the edge of the casing and, in the present instance, the two tongues are 80 connected one to the other by a bolt 7 which serves as a binding post. As has been 85 stated, the inner faces of the two sections of the casing are spaced apart and inasmuch as the condenser plates are mounted in and 90 flush with the walls of this chamber it will be apparent that the condenser plates are 95 spaced apart and may receive between them a movable condenser plate. The movable condenser plate is shown at 8 and is also substantially semi-circular in shape. It is mounted for rotation within the chamber of the casing so that it can be moved wholly 100 into the space between the two stationary condenser plates or entirely withdrawn from that space. In the present construction the 105 movable plate is mounted on a short, hollow shaft 9 which is journaled in the two sections of the casing and is, in the present instance, provided with an integral collar 10 between which and a movable collar 11 the hub portions 12 of the movable condenser plate is clamped so as to rigidly connect the same with the shaft 9. The collar 11 may 110 be positioned on the shaft 9 in any suitable

manner but is preferably pressed onto the same. Mounted within the chamber of the casing and arranged between the movable condenser plate 8 and the respective stationary condenser plates 4 are two sheets 13 of suitable dielectric material, such as mica, and in the construction here shown, these sheets of mica are in the form of disks having central openings to permit them to be mounted about the hollow shaft 9. Their shape and arrangement is such that they will at all times completely separate the stationary condenser plates from the movable condenser plate and it is immaterial whether or not they are held rigidly against movement. By the use of these sheets of dielectric material I am enabled to greatly reduce the distance between the condenser plates and still maintain a high insulation value between them. The movable condenser plate may be connected in the circuit in any suitable manner, but in the present form of the device each section 1 of the casing is provided with a connector bar 14, the inner end of which, 15, encircles the hollow shaft 9 and is maintained in firm electrical connection with a part of that shaft and, therefore, with the movable plate. Preferably the opening in the hub portion 15 of each connector bar 14 is surrounded by a laterally extending flange 16 which enters the opening in the section of the casing and forms a bearing in which the shaft 9 is journaled. As here shown, the connector bars are molded in the two sections of the casing and their outer ends are brought together and connected by a bolt 17 which constitutes a binding post. If desired, additional means may be provided for insuring a firm electrical contact between the connector bars and the hollow shaft 9, and, in the present instance, I have interposed resilient washers 18 between the collars 10 and 11 and the hub portions of the respective connector bars.

Any suitable means may be provided for rotating the shaft 9 and thus adjusting the movable condenser plate but I prefer that the shaft 9 shall be provided at one or both end portions with a socket 19 which may be non-circular in shape to receive the end of an operating shaft 20, the end of which is shaped to fit within the socket 19. The end portions of the shaft 9 are provided with annular recesses 21 and the shaft 20 has a collar 22 which fits within one of these annular recesses and limits the inward movement of the shaft. The shaft has mounted on its outer end an operating handle, such as a knob, 23, and if desired there may be connected with the shaft a suitable indicator to indicate to the operator the position of the movable condenser plate. As here shown, a dial 24 is rigidly secured to the knob 23 so as to rotate in

unison with the shaft. This dial may be provided with a series of indications with which may cooperate a fixed pointer, or indication, on the side wall of the indicator but these indications are not here shown as they form no part of the invention.

The condenser thus provided is of a small compact form and has a relatively large capacity. If it is desired to utilize two or more of these condensers as a single condenser in order to increase the capacity thereof, this may be done by connecting together two condensers, or units, of the type above described. The two units may be connected by means of bolts of sufficient length to extend through both condensers. The shafts 9 of the two units may be operated in unison by a single controlling device by connecting the same one to the other, as shown in Fig. 6. To accomplish this I provide a suitable connecting shaft 25, the end portions of which are non-circular to fit into the sockets of the two condenser shafts. Preferably the non-circular portions of the shaft are separated by a collar 26 which fits into the annular recesses 21 in the ends of the shafts 9, and thus correctly positions the connecting shaft with relation to the condenser shafts. It will be apparent that when the shafts of two or more condenser units have been connected in this manner they will all be rotated simultaneously by the manipulation of the controlling handle, or knob, 23.

In the operation of radiophone receiving sets it is preferable that the initial adjustment, or "tuning in", be accomplished by the use of a condenser of relatively large capacity, and that the finer adjustments should be accomplished by a supplemental condenser of smaller capacity. I have, in Fig. 1, shown a supplemental condenser of such a character that it can be connected with one of the condenser units and made an integral part thereof, but may be controlled and operated separately from the main condenser. As here shown, the supplemental condenser consists of a casing 27 adapted to be secured to the wall of the main condenser and arranged to form within the same a chamber. In the present device the casing for the supplemental condenser is in the form of a disk of insulating material of the same diameter as the sections 1 of the main casing and is provided with a circumferential laterally extending flange 28 which bears against the adjacent section 1 of the main casing and thus spaces the intermediate portion of the inner wall of the casing 27 away from the wall of the section 1 and provides the desired chamber. The casing 27 may be attached to the casing 1 in any suitable manner as by extending the screws 3 through both casings. Mounted within the chamber in the casing 27 is a movable condenser member, or plate, 29, which is mounted on a hol-

low shaft 30 rotatably mounted in the casing 27. As here shown, the shaft has an integral collar 31 between which and a movable collar 32 the hub portion of the movable condenser plate is clamped, it being understood that this plate is substantially similar to the condenser plate 8 shown in Fig. 3. The collar 32 is provided with a hub portion 33 which is rigidly secured to the shaft 30, preferably by pressing the same thereon and which forms the journal, or bearing, portion of the shaft 30. The inner end of the shaft 30 extends into the adjacent end of the hollow shaft 9 of the main condenser but is of a smaller diameter than the socket in the hollow shaft so that the shaft 30 can rotate relatively to the shaft 9. The movable condenser plate 29 is connected in the circuit by means of a connector bar 34 which is substantially similar to the connector bar 14 of Fig. 8. This connector bar is mounted in the casing 27 and has a hub portion 35 which forms a bearing for the hub portion 33 of the collar 32. The outer end of the connector bar 34 extends beyond the edge of the casing and is preferably connected with the outer ends of the connector bars 14, this being accomplished by extending the bolt 17 through the several connector bars. The shaft 30 may be rotated in any suitable manner, but in the present construction the operating shaft 20 for the main condenser is hollow and extending through this hollow shaft is another shaft 36, the end of which is screw threaded into the hollow shaft 30 of the vernier condenser and extends beyond the same where it is provided with a locking nut 37. The opposite end of the shaft 36 has rigidly secured thereto an operating handle, or knob, 38. It will be apparent therefore, that the movable members of the two condensers are rotatable about a common axis but that they are independently controlled so that one may be adjusted relatively to the other, and that the movable plate of the supplemental condenser cooperates with the nearest fixed plate of the main condenser.

While I have shown and described one embodiment of my invention I wish it to be understood that I do not desire to be limited to the details thereof as various modifications may occur to a person skilled in the art.

Having now fully described my invention what I claim as new and desire to secure by Letters Patent, is:

1. In a condenser, a casing comprising two sections of insulating material rigidly connected one to the other and arranged to form a chamber between them, two condenser plates molded into the respective sections of said casing, and arranged side by side but spaced one from the other, a movable condenser plate mounted in said chamber for rotatory movement into and out of

the space between the first mentioned plates, and sheets of dielectric material arranged between said movable plate and the respective first mentioned plates.

2. In a condenser, a casing comprising two sections of insulating material rigidly connected one to the other, a condenser plate molded into each of said sections and having its inner face substantially flush with the adjacent portions of said section, said sections having cooperating parts to space said condenser plates one from the other, a shaft journaled in said casing, a condenser plate mounted on said shaft and arranged to be moved into and out of the space between the first mentioned condenser plates, and means for rotating said shaft.

3. In a condenser, a casing comprising two substantially similar sections of insulating material each having a laterally extending circumferential flange, the flanges of the two sections being arranged to abut one against the other and form a chamber between said sections, condenser plates rigidly secured to the inner faces of the respective sections, a shaft journaled in said casing, a movable condenser plate mounted on said shaft for movement into and out of the space between the first mentioned plates, and sheets of dielectric material interposed between said movable condenser and the respective first mentioned condenser plates.

4. In a condenser, a casing comprising two sections of insulating material, connected one to the other and arranged to form a chamber between them, two condenser plates rigidly supported within said chamber and spaced apart, a shaft journaled in said casing, a condenser plate rigidly secured to said shaft and movable into and out of the space between the first mentioned condenser plates, a connector bar mounted in said chamber and having a part embracing said shaft and held in firm electrical contact therewith, and sheets of dielectric material interposed between said condenser plate and said stationary condenser plates.

5. In a condenser, a casing comprising two sections of insulating material rigidly connected one to the other and arranged to form a chamber between them, two condenser plates rigidly supported within said chamber and spaced apart, a shaft having its ends journaled in the respective sections of said casing, a condenser plate having a hub portion embracing said shaft, means for rigidly securing the last mentioned condenser plate to said shaft, means for rotating said shaft to cause said last mentioned condenser plate to be moved into and out of the space between the first mentioned condenser plates, and sheets of dielectric material interposed between said movable condenser plate and said first mentioned condenser plates.

4

6. In a condenser, a casing comprising two sections of insulating material rigidly connected one to the other and arranged to form a chamber between them, two condenser plates rigidly supported within said chamber and spaced apart, a hollow shaft having its ends journaled in the respective sections of said casing, a condenser plate rigidly secured to said shaft and movable into and out of the space between the first mentioned condenser plates, sheets of dielectric material interposed between said movable condenser plate and the respective first mentioned condenser plates, an operating shaft having a portion adapted to enter one end of said hollow shaft, and a connecting member having its two ends adapted to enter the adjacent ends of the hollow shafts of two condensers placed face to face, thereby connecting the movable plates of the two condensers for simultaneous operation.

7. The combination with a condenser comprising a casing, consisting of two sections

of insulating material rigidly connected one to the other and arranged to form a chamber between them, stationary condensing plates mounted within said chamber, a shaft journaled in said chamber, a condenser plate mounted on said shaft for movement into and out of the space between said stationary condenser plates, and a hollow operating shaft operatively connected with the first mentioned shaft, of a supplemental casing rigidly secured to the first mentioned casing, a shaft journaled in said supplemental casing in axial alinement with the first mentioned shaft, a condenser plate carried by the last mentioned shaft, and an operating shaft extending through said hollow operating shaft and operatively connected with the shaft in said supplemental casing.

In testimony whereof, I affix my signature hereto.

WILLIAM H. PETIT.
